UNITED STATES PATENT OFFICE

101,521

DESIGN FOR A BOOK RACK OR SIMILAR ARTICLE

Fred D. Farr, Mamaroneck, N. Y., assignor to
Revere Copper and Brass Incorporated, Rome,
N. Y., a corporation of Maryland

Application August 27, 1935, Serial No. 58,324

Term of patent 14 years

To all whom it may concern:

Be it known that I, Fred D. Farr, a citizen of the United States and a resident of Mamaroneck, county of Westchester, State of New York, have invented a new, original, and ornamental Design for a Book Rack or Similar Article, of which the following is a specification, reference being had to the accompanying drawing, forming part thereof.

In the drawing:—

Fig. 1 is a side elevational view of a book rack or similar article, showing my new design; and

Fig. 2 is a section on the line 2—2 of Fig. 1 with parts shown in elevation.

The dominant feature of my design is a relatively flat central abutment member with flat curved springs at opposite sides thereof serving to hold flat articles against said member, the abutment extending relatively far above said springs and serving as a handle member for the device.

I claim:

The ornamental design for a book rack or similar article, substantially as shown and described.

FRED D. FARR.
